UNITED STATES PATENT OFFICE.

HENRY G. VOIGHT, OF NEW BRITAIN, CONNECTICUT.

LOCK.

1,040,966.

Specification of Letters Patent.

Patented Oct. 8, 1912.

Application filed August 26, 1911. Serial No. 646,260.

To all whom it may concern:

Be it known that I, HENRY G. VOIGHT, a citizen of the United States, residing at New Britain, Hartford county, State of Connecticut, have invented certain new and useful Improvements in Locks, of which the following is a full, clear, and exact description.

My invention relates to locks and latches. 10 The object of my invention is to produce a lock of the so-called unit type, that is, a lock in which the several parts, including knobs, escutcheons, etc., may be assembled independently of the door to which the lock 15 is applied, for the purposes of perfecting the various adjustments at the factory. In such a lock I have devised improvements whereby the same may be very quickly applied to a door, the mortises therein being 20 formed with a single tool, such as a bit or auger.

Various other advantages and improvements will be apparent to a mechanic skilled in this art by a reading of the following description:

In the drawings, Figure 1 is a plan view, partly in section, of my improved lock as it would appear in place on a door. Fig. 2 is a longitudinal section through substantially the center of the lock showing certain parts in elevation, said section being in a plane at a right angle to the plane of Fig. 1. Fig. 3 is a longitudinal section of a detail. Fig. 4 is a cross section on the 35 plane of the line $x-x$, Fig. 3. Figs. 5, 6, 7 and 8 each show two different views of different details.

1 represents the edge of a door, as shown. The mortise for the lock is formed by 40 boring only two holes in the door stile. One hole is bored transversely through the door stile, the axis thereof being coincident with the axis of the knobs. The other hole is bored into the edge of the door stile so as 45 to intersect the middle of the transverse bore first referred to.

2 represents a bolt, in this instance a spring latch bolt.

3 represents a face plate through which 50 the bolt 2 passes. The face plate may be of any suitable design.

4 is a cylindrical guide and carrier for the bolt 2. The bolt 2 is arranged to reciprocate in the carrier 4.

5 is a spring within the carrier, and arranged to project the bolt 2.

6 is a block on the latch slide 6^a. The tail 7 is the tail of the bolt. The tail of the bolt is adjusted in connection with the block 6 by being threaded therein. 60

8 is a lock nut. The carrier 4 screws into the cylindrical main body or frame 9 and projects radially therefrom. The length of the carrier 4 and the adjustment of the latch 2 determines the 65 "set back" of the lock. The frame 9 is provided at one end with a side plate 10.

11 is a rose or knob bearing adapted to the passage through the plate 10. 12 is a knob rotatably mounted in the 70 rose 11.

13 is a frame in the form of a side plate which is arranged to stand on the opposite side of the door from the plate 10. This plate is adjustable to and fro relatively to 75 plate 10 by screws which are merely shown in section at 14—14, Fig. 2.

15—15 is a knob which stands opposite the knob 12.

16 is a rose bearing for the knob 15, said 80 bearing being mounted in the plate 13.

Any suitable adjustable connection may be provided between the knobs 12—15 whereby there will be no interference in the adjustment of the side plates 10—13 toward and from each other. As shown in the drawings, the knob 15 in this case represents the outside door knob and may be provided with the usual key controlled mechanism inclosed therein, the same being indicated in dotted outline. This key-controlled locking mechanism is designed to control the operation of one roll back, in this instance indicated at 17. The knobs 12—15 may control respectively the roll-backs 18—19. The roll-back 19 may have at one side thereof a notch or locking recess 19^a (see Fig. 8).

20 is a locking dog, the nose of which is adapted to be projected into the notch 19^a 100 whenever desired to prevent the turning of the outer knob 15. The dog 20 may be mounted in any suitable way at the inner side of the lock where it is accessible from the inside of the door for manual manipulation. The particular method of mounting this dog is immaterial, although in this particular instance it is shown as mounted to slide upon the inner surface of the inside side plate 10, the same being slotted at 10^a 110 to permit a projection from the slide 20 to pass through said slot so as to be provided

with a suitable operating button to receive finger pressure, said operating button being indicated in dotted lines at 20^a.

21 is a spring pressed detent for frictionally holding the dog in either the "in" or the "out" position.

It will be observed that the guide 4 is always held in definite position relative to the knob 12 by reason of the fact that both 10 the guide and the knob 12 are held in definite spaced relation by the main body or frame 9, hence the entire adjustment for the purposes of associating the lock with doors of different thicknesses is effected 15 through the shifting of the outer side plate and the outer knob and associated parts.

The roll-backs 17, 18 and 19 are all arranged to operate independently, hence, when the outer knob 15 is locked, the latch 20 bolt 2 may still be operated by the inner knob 12 or by the key controlled roll-back 17.

What I claim is:

1. In a lock of the character described, in 25 combination, a main frame embodying a cylindrical casing, a knob bearing at one end of said casing, a knob mounted therein having a spindle, a threaded bore formed in said casing transversely thereof, a bolt slide and 30 coöperating roll back mechanism carried by said frame, said frame and its associated parts forming an assembled unit adapted to be secured to and inserted in one side of a door, a side plate having a knob bearing 35 and a knob and spindle mounted therein, adapted to be secured to the opposite side of the door and arranged to be alined with and operatively connected to the parts of said main frame, said plate and its associated 40 parts forming a second and independent assembled unit adapted to be inserted in the opposite side of said door independently of said first assembled unit, a cylindrical bolt 45 guide having its end formed for threaded engagement with said casing bore to extend radially from said casing, and a bolt arranged within said guide having its end formed for threaded engagement with said slide.

50 2. In a lock of the character described, in combination, a main frame embodying a cylindrical casing, a knob bearing at one end of said casing, a knob mounted therein having a spindle extending through said casing, a threaded bore formed in said casing transversely thereof, a cylindrical bolt guide having its end in threaded engagement with said bore and extending radially from its casing, a bolt slide within said casing, a 55 bolt arranged within said guide having its end in threaded engagement with said slide, roll back mechanism positioned to engage said slide to operate said bolt, a side plate arranged to be alined with and adjustably 60 connected to said main frame, a knob bear-

ing carried by said plate and a knob and spindle mounted therein and adjustable with said plate, said knob spindles being operatively connected with said roll back mechanism.

70 3. In a lock of the character described, in combination, a main frame embodying a cylindrical casing, a knob bearing at one end of said casing, a knob mounted therein having a spindle, a threaded bore formed in said casing transversely thereof, a bolt slide and two coöperating roll backs carried by said frame, said frame and its associated parts forming an assembled unit, a side plate having a knob bearing and a knob and spindle mounted thereon adapted to be secured to the opposite side of the door, said parts forming a second assembled unit, threaded alining pins carried by said main frame and engaging and adjustably spacing 80 said side plate and its associated parts therefrom; the spindle of said second assembled unit having an adjustable connection with one of said roll backs, a cylindrical bolt 85 guide having its end formed for threaded engagement with said casing, and a bolt arranged within said guide having its end formed for threaded engagement with said slide.

90 4. In a lock of the character described, in combination, a main frame embodying a cylindrical casing, a knob bearing at one end of said casing, a knob mounted therein having a spindle, a threaded bore formed in said casing transversely thereof, a bolt slide and three coöperating roll backs carried by said frame, said frame and its associated parts forming an assembled unit, a side plate having a knob bearing and a knob and spindle mounted thereon adapted to be secured to the opposite side of the door, said parts forming a second assembled unit, threaded alining pins carried by said main frame and engaging and adjustably spacing 95 said side plate and its associated parts therefrom; the spindle of said second assembled unit having an adjustable connection with a roll back, the spindle of said first mentioned unit being operatively connected to a second roll back and key controlled 100 mechanism for operating the third roll back.

105 5. A sectional unit lock of the character described comprising two complementary and assembled sections adapted to be inserted as independent unitary structures through opposite sides of a bore extending transversely through a door, each sectional unit embodying a supporting frame having a knob and a knob spindle mounted therein, one of said sectional units carrying a bolt slide and roll-back mechanism, and said complementary sections being automatically and operatively connected when so inserted in said transverse bore; and a third and independent sectional unit adapted to be inserted through 110 115 120 125 130

- a bore in said door extending longitudinally thereof and intersecting said first named bore, said third sectional unit embodying an assembled bolt guide and bolt and said bolt being constructed and arranged to be adjustably and operatively connected to said bolt slide.
6. A sectional unit lock of the character described, comprising two complemental and 10 assembled sections adapted to be mounted as independent unitary structures upon opposite sides of a door and to be inserted within a bore formed therein and extending transversely therethrough, each sectional unit 15 embodying a supporting frame having a knob and a knob spindle mounted therein, one of said sectional units having a cylindrical body portion fitting within said bore and carrying a plurality of roll-backs, and 20 a bolt-slide within said cylindrical body portion and in operative connection with said roll-backs, and said sectional units and the operating mechanism carried thereby being constructed and arranged for relative alined
- adjustment and automatically and operatively connected when so inserted and adjusted; a third sectional unit adapted to be inserted through a bore in said door extending longitudinally thereof and intersecting said first named bore, said cylindrical body portion having an aperture therein positioned for alinement with said bolt guide when the parts are mounted, and said bolt guide adjustably engaging said cylindrical body portion and having a bolt slidably 35 mounted therein and constructed and arranged to extend through the aperture in said cylindrical body portion and to be adjustably and operatively connected to the bolt slide therewithin; and means whereby 40 said two complemental sectional units may be adjusted relative to and in alinement with each other to accommodate said parts to doors of different thicknesses.
